UNITED STATES PATENT OFFICE.

GEORGE H. PEIRCE, OF WAKEFIELD, MASSACHUSETTS.

DENTAL TOOL.

SPECIFICATION forming part of Letters Patent No. 443,705, dated December 30, 1890.

Application filed May 8, 1890. Serial No. 351,071. (No model.)

To all whom it may concern:

Be it known that I, GEORGE H. PEIRCE, a citizen of the United States of America, residing at Wakefield, in the county of Middlesex and State of Massachusetts, have invented certain new and useful Improvements in Dental Tools, of which the following is a specification, reference being had therein to the accompanying drawings.

10 My invention relates to that class of dental tools commonly known as a "disk carrier or holder," and it is the object of my invention to provide a simple form of holding-mandrel adapted to receive the disks with 15 means for clamping the disks securely when in use, the construction being such as to allow the ready removal of the worn disks and the substitution of others.

My invention consists in a mandrel having 20 a face-plate upon its end provided with spurs, a central opening in the end of the mandrel, a head having a screw-threaded stem adapted to the central opening, and a split portion below the face-plate forming a part of the 25 circumference of the mandrel, but not a part of the face-plate. This split portion has a series of teeth or a single tooth adapted to engage with the threads of the stem when the said split portion is forced inward by a sliding collar. By this construction I hold the 30 head positively against displacement, at the same time allowing it to be easily removed and as easily inserted.

In the accompanying drawings I have represented the mandrel in side elevation in 35 Figure 1, and in Fig. 2 I have shown a central section longitudinally of the end thereof.

The shank of the mandrel, as shown at *a*, is adapted for connection with any suitable 40 holder, and power may be transmitted to rotate the mandrel in any suitable manner. This forward end is provided with a face-plate *b*, having a series of spurs projecting from its surface, these spurs being adapted 45 to penetrate the material of the disk, which is placed upon them. A central opening passes through the face-plate extending into the body of the mandrel, this opening being perfectly plain, and it is adapted to receive

the screw-threaded stem *c* of the head *d*, the 50 opening being of a diameter equal to or slightly exceeding that of the stem, so that the said stem will slip into the opening easily and be capable of as easy removal. The disk is clamped between the under face of the head 55 and the face-plate, the spurs preventing independent rotation of the disk.

In order to hold the stem of the head in position I provide the mandrel in rear of the face-plate with a split portion, as at *e*, this 60 being, preferably, of spring metal, so as to stand normally outside the line of the circumference of the shank of the mandrel. I prefer to have this split portion made integral at its rear end with the material of the mandrel, 65 though it may be made of a separate piece and held in place by a pivot or otherwise. The inner face of the split portion is provided with a single spur or a series of teeth, which when the split portion is pressed inward 70 engages the threads of the stem, and thus prevents the removal of the head so long as the split part is pressed inward.

I do not limit myself to a threaded stem for the head, as it may be provided with a series 75 of notches or a series of parallel depressions, though it is desirable to have the ordinary spiral thread, as more perfect adjustment can thus be secured. In order to press the split portion inward I arrange a sliding collar or sleeve, which encircles the shank of the mandrel, as shown at *f*, and as this sleeve is moved outward toward the end the split portion is pressed inward until its spur or teeth engage with the threaded stem of the 85 head. To remove the head it is only necessary to slide back the sleeve, which will allow the split portion to spring outward, and the head will then be free to be removed.

I claim as my invention—

1. The described dental tool, consisting of a shank or mandrel, a face-plate carried thereby, a central opening passing through the face-plate and into the shank, a head having a stem adapted to enter said opening, and a 95 part, as *e*, having a spur or teeth for engaging said stem, and means for operating said part *e*, substantially as described.

2. In combination with the mandrel having a face-plate with spurs, a split portion in rear of said face-plate, a head having a screw-threaded stem adapted to enter an opening 5 in the face-plate and mandrel, said split portion having teeth or a spur for engagement with the threaded stem, substantially as described.

In testimony whereof I affix my signature in presence of two witnesses.

GEORGE H. PEIRCE.

Witnesses:

HENRY H. ARNOLD,
M. J. CHIRAZIAN.
